United States Patent

Des. 235,587
Patented June 24, 1975

235,587

SIGNBOARD

Jefferson D. Muse, 156 Forsythe St. SW.,
Atlanta, Ga. 30306

Filed Jan. 14, 1974, Ser. No. 433,349

Term of patent 14 years

Int. Cl. D20—03

U.S. Cl. D96—12

FIG.1

FIG.2

FIG. 1 is a front elevational view of a signboard showing my new design, the rear being a mirror image of the front shown; and

FIG. 2 is an elevational view taken from one end thereof, the opposite end being a mirror image of the end shown.

The broken line showing of indicia in FIGS. 1 and 2 is for purposes of illustration only.

I claim:

The ornamental design for a signboard, substantially as shown and described.
